(57) **CLAIM**

The ornamental design for a point of sale terminal with advertising monitors, as shown and described.

DESCRIPTION

FIG. 1 is a front perspective view of a point of sale terminal with advertising monitors;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof; and,

FIG. 7 is a bottom plan view thereof.

The broken line showing in FIGS. 6 and 7 are for the purpose of illustrating environmental subject matter, such as receipt printout slots, communication ports and channels for routing cables, and form no part of the claimed design.

1 Claim, 7 Drawing Sheets
